JOHN J. CHAPIN, OF DETROIT, MICHIGAN, ASSIGNOR TO BURROUGHS ADDING MACHINE COMPANY, OF DETROIT, MICHIGAN, A CORPORATION OF MICHIGAN.

TYPE-WRITER RIBBON MECHANISM.

1,163,111.

Specification of Letters Patent. Patented Dec. 8, 1915

Application filed September 2, 1908. Serial No. 451,363.

To all whom it may concern:

Be it known that I, JOHN J. CHAPIN, a citizen of the United States, residing at Detroit, in the county of Wayne and State of Michigan, have invented certain new and useful Improvements in Type-Writer Ribbon Mechanism, of which the following is a specification.

The present invention relates to mechanism for controlling the ink ribbon of a typewriting or like machine and one object of the invention is to provide for automatically discontinuing the ribbon feed during a tabulating advance of the paper carriage.

Another object is to provide a simplified form of ribbon vibrator for a front-strike typewriter and a third object is to provide improved means for transmitting movement from the spring drum to the ribbon shaft.

With these and incidental objects in view the invention consists in certain novel features of construction and combinations of parts, the essential elements whereof are recited in the appended claims and a preferred form of embodiment of which is described in detail hereinafter and fully illustrated in the accompanying drawings forming a part of this specification.

Of said drawings Figure 1 represents a partial top plan view of a typewriting machine having the improvements of the present invention embodied therein; Fig. 2 is a fragmentary sectional elevation of the machine, the view being taken a short distance inside the left-hand frame-piece; Fig. 3 is a similar view, the view being taken farther to the left; Fig. 4 is a sectionalized top plan view of ribbon-driving mechanism; Fig. 5 is a cross-sectional detail taken on the line 5—5 of Fig. 4; Fig. 6 is a horizontal view of the ribbon vibrator and guide; Fig. 7 is a perspective view of a ribbon vibrator; Fig. 8 is a detail front elevation of part of the ribbon feed mechanism; and Fig. 9 is a sectionalized front elevation of another portion of the ribbon feed mechanism.

The ribbon spools 2 and 3 are suitably mounted upon horizontal shafts 4 and 5 so as to turn therewith and the ribbon runs out over suitable sheaves 6 and 7 and through the vibrator in front of the roller platen 8 as shown in Fig. 1. The shafts 4 and 5 carry beveled gears 9 and 10 adapted to mesh with similar gears 11 and 12 secured to a shaft 13 which is mounted to slide and

rotate in suitable bearings on the frame work, the relation between the beveled gears being such that the intermeshing pairs alternately engage. A grooved collar 14 on the shaft co-operates with a spring clip 15 on the framework to hold the said shaft in its two different positions. Motion is transmitted to said shaft from the carriage spring barrel 16 through the following described train of mechanism: A ratchet wheel 17 secured to said barrel engages with a spring-pressed pawl 18 pivoted upon a large gear wheel 19 concentric with the barrel but loosely mounted relative thereto. This gear wheel meshes with a smaller gear wheel 20 supported by a suitable bracket 20' and held from retrograde movement by a gravity dog 21 (Fig. 8). This smaller gear wheel is secured to a shaft 22 which carries a worm 23. The latter meshes with a worm wheel 24 secured to a sleeve 25 loosely mounted upon a sleeve 26 which is secured to the shaft 13 (Fig. 4). The sleeve 25 is held from longitudinal movement by reason of the engagement between two flanges 27 on the sleeve of a finger 29 secured to and projecting from a bracket in which the spring drum is mounted. A pin 30 secured in the outer one of the two flanges 27 slides through an opening in the flange of a sleeve 31 loose on the shaft 13 but movable longitudinally therewith. This sleeve 31 abuts the sleeve 26 at one end and at the other end carries a ratchet wheel 32 (Fig. 5). This ratchet wheel is engaged by a pawl 33 pivoted upon the flange of a collar 34 secured to the shaft 13, the said pawl being spring-pressed into engagement with the ratchet.

It will be obvious that through the above-described connections the turning of the spring barrel in one direction, to-wit, the direction in which it turns when the carriage is being drawn to the left, will rotate the shaft 13 and turn one or the other of the two ribbon spools, thus winding the ribbon on one spool and unwinding it from the other. Rotative engagement between the worm gear wheel 24 and the shaft is maintained through the sliding engagement of the pin 30 with the flange of the sleeve 31 so that the worm and worm gear remain constantly in mesh. The shaft 13 may be turned by hand without affecting the driving connections with the drum, the pawl 33

in such case simply clicking over the ratchet 32. For the purpose of turning the ribbon spools by hand the shaft 13 is equipped with a handle crank 35, as shown in Figs. 1 and 4.

5 In order to suspend advance or feed of the ribbon when the carriage moves a number of spaces at once as in tabulating, provision is made for disconnecting the spring drum from the ribbon feed shaft 13 as an 10 incident to a tabulating operation. In Fig. 2 tabulating connections are shown, the same comprising a key lever 40 pivoted intermediate its ends and carrying in rear of its pivot a supplemental lever 41 also pivoted intermediate its ends, said supplemental lever being drawn down by a spring 42 on its forward side. A latch 43 pivoted to the frame-work and drawn rearwardly by a spring 44 normally engages over a pin or 15 stud 45 on said lever 41, preventing such lever being carried up bodily by the lever 40 when the key on the front end of the latter is depressed. The rear end of said lever 40 is formed with a depending extension 46 carrying a stud 47 to co-act with a cam rise 48 on the latch 43 so that as the tabulating key reaches the end of its downward movement the latch 43 will be disengaged from the stud 45 and the spring 42 which has 20 meantime been put under tension will thereupon throw up the rear end of the lever 41 against a stop stud 49 on the lever 40. A rod 50 connects the rear end of said lever 41 with an arm 51 loose upon a rock shaft 52, 25 the latter extending in rear of the spring drum. This rock shaft has affixed to it an angular arm 53 connected with said arm 51 by a comparatively strong spring 54 and having a stud 55 which engages under said 30 arm 51. Thus it will be seen that depression of the tabulator key will result in said shaft 52 being rocked. An arm 56, secured to said rock shaft and projecting forward, carries a roller 57 engaging under a flange 58 of the 35 escapement rack 59, the latter being carried by pivoted arms 60 and normally engaging an escapement pinion 61. The rocking of the shaft 52 by depression of the tabulator key is utilized as a means for discontinuing 40 the ribbon feed. Thus there is secured to said shaft a short downwardly-extending radial arm 63 having a spherical enlargement 64 at its end for operating against one 45 end of a rod 65 which slides through a tubular shaft 16^a supporting the spring barrel. This rod is screw-threaded at its rear end to receive a nut 66 which confines a spring 67, the latter holding the rod normally rearward. This rod protrudes from the front 50 side of the drum and beyond the large gear 19 and carries a conical head 68. The pawl 18 is formed with a cam finger 69 bent out and over the conical head 68. It will be seen that the rocking of the tabulator shaft 55 52 will thrust the rod 65 forward and cause

its conical head 68 to act with a camming effect upon the finger 69, thus disengaging the pawl 18 from the ratchet 17 thereby discontinuing the ribbon feed. When the tabulator key rises of course the rock shaft 52 70 is restored to normal and the thrust rod retreats permitting the ratchet to reengage the pawl. Depression of the tabulator key sets a suitable stop to limit the movement of the carriage.

Passing now to the ribbon vibrator this is made of a single piece of sheet metal comprising a shank 80, (Fig. 7) divergent arms 81 springing from a slightly off-set portion 80' of the shank, vertical extensions 82 of 80 said arms and doubled-over integral portions 83 between which and the portions 82 the ribbon is confined. Small ledges 84 are bent forward at the upper edges of the horizontal portions of the branches 81 to support the lower edge of the ribbon on flat surfaces avoiding wear on the edge of the ribbon. With this construction the ribbon is properly held in front of the platen with the minimum of metal above the same so that the work is not at all obstructed by the presence of the vibrator. The latter is guided in its movements up and down by a portion of a type bar centering guide 85 vertically extending parts of the latter being 85 grooved along opposite sides to receive clips 86 formed out of the vibrator metal springing from opposite edges of the same just above the offset 80' and projecting forward and thence toward each other. Up and 90 down movement of the vibrator is produced through appropriate connections with the letter-spacing mechanism. Thus there is jointed to the lower extremity of the vibrator the forward end of a lever 90 (Fig. 3) 105 which is pivoted intermediate its ends to a bracket 91 and at its rear end embraces a screw-threaded rod 92 between adjusting nuts 93. Said rod is connected with a link 94 which is held upward by a spring 95 and 110 coupled to a bell crank lever 96. This bell crank lever is connected by a link 97 to an up-standing arm 98 of a universal bail 99 running under the key levers.

It will now be seen that the constructions 115 above described are well calculated to fulfil the objects primarily stated though it is to be understood that such constructions are susceptible of modification within the scope of the invention.

What I claim is:

1. In a machine of the character described, the combination of a paper carriage, a spring drum and connections for moving said carriage, ribbon carrying means, gearing applied to the latter and including a member adjacent the spring drum, ratchet and pawl connecting the latter and said member, a tabulator key and connections, and means for throwing out the ratchet and 120 125 130

- pawl connection by operation of said tabulator key.
2. In a machine of the character described, the combination of a paper carriage, a 5 spring drum and connections for moving said carriage, ribbon carrying means, gearing applied to the latter and including a member concentric with the spring drum, a ratchet wheel adjacent said member, a 10 spring held pawl on the latter engaging said ratchet wheel, a tabulator key and connections including a rock shaft with a radial projection, and a slide rod extending axially of the drum and acted upon by said radial 15 projection and in turn acting upon said pawl to disengage it from the ratchet wheel.
3. In a machine of the character described, the combination of a paper carriage, a spring drum and connections for moving 20 said carriage, ribbon carrying means, gearing applied to the latter and including a member concentric with the spring drum, a ratchet wheel adjacent said member, a spring held pawl on the latter engaging 25 said ratchet wheel, and having a cam finger, a tabulator key and connections including a rock shaft with a radial projection, and a slide rod extending axially of the drum and acted upon by said radial projection 30 and having a conical head engaging the cam finger of the pawl; substantially as and for the purpose described.
4. Ribbon feed mechanism comprising spools and their gears; a rotatable slide 35 shaft carrying gears to mesh alternately with corresponding spool gears; a sleeve loose on the shaft and held from movement longitudinally thereof and having a worm gear; a worm permanently in mesh with 40 said gear; means for driving the worm; a second sleeve loose on the shaft but movable longitudinally therewith and rotatably engaged with the first sleeve; and a ratchet and pawl driving connection between the 45 last-mentioned sleeve and the shaft.
5. In a machine of the class described, a
- one-piece ribbon vibrator comprising a shank and spaced fingers doubled over to form ribbon guides and bent over portions laterally offset from the fingers constituting 50 ledges to support the ribbon edgewise.
6. In a machine of the class described, a one-piece ribbon vibrator comprising a shank, divergent branches having upstanding fingers doubled over to form ribbon 55 guides, the divergent branches having bent over portions offset laterally from the fingers constituting ledges to extend under the ribbon.
7. In a typewriting machine, the combination of a type bar centering guide vertically grooved in opposite sides, and a one-piece ribbon vibrator having a shank with angular clips to engage the grooves in the type-bar guide and arms in continuation of 60 the shank.
8. In a typewriting machine, the combination of a type bar centering guide vertically grooved in opposite sides, and a one-piece ribbon vibrator having a shank with angular 70 clips to engage the grooves in the type bar guide, and arms in continuation of the shank with fingers bent over toward the plane of the engaging portions of the clips.
9. In a machine of the character described, 75 the combination of a paper carriage, a spring drum and connections for moving said carriage, ribbon carrying means, gearing applied to the latter and including a member concentric with the spring drum, 80 clutch connections between the spring drum and said concentric member, a tabulator key and connections including a rock shaft with a radial projection and a slide rod extending axially of the drum and acted upon 85 by said radial projection and in turn controlling said clutch connections.
